UNITED STATES PATENT OFFICE

HENRY SONDERSEN AND HENRY GLEMMING, OF BROOKLYN, NEW YORK

TROUSERS STRETCHER

Application filed December 2, 1930. Serial No. 499,548.

The present invention relates to new and useful improvements in garment stretchers, and more particularly it pertains to a device for pressing and creasing, and for taking the bag out of the knees of men's trousers.

It is one of the objects of the invention to provide a device of the aforementioned character which may be inserted into the leg portion of a pair of trousers in order that the said 10 leg portion may be stretched to proper form and the bag removed from the knee portion thereof.

It is a further object of the invention so to construct a device of the aforementioned 15 character that it may be adjustably fitted to trousers legs of varying sizes.

It is a further object of the invention so to construct a device of the aforementioned character that it may be folded when not in 20 use and thereby reduced in size in order that the same may be more readily portable or require comparatively less space in storage.

A further object of the invention resides in 25 a novel means whereby the trousers legs are provided with a crease after they have been left upon the stretcher sufficient time.

With the above and other objects in view, reference will be had to the accompanying 30 drawings forming a part of this application, and in which;

Figure 1 is a perspective view of a trousers stretcher constructed in accordance with the present invention, illustrating the same in its 35 extended form,

Figure 2 is a view in elevation illustrating the manner in which the device is used,

Figure 3 is an edge view of Figure 2,

Figure 4 is an edge view illustrating the 40 device in its folded position,

Figure 5 is an enlarged detail fragmentary view illustrating the pivotal construction of the device,

Figure 6 is a transverse sectional view taken 45 through one of the frame members of the device,

Figure 7 is a fragmentary perspective view illustrating the construction of one of the elements of the frame member,

50 Figure 8 is a similar view showing the

parts in a partially folded position; and; Figure 9 is a detail perspective view.

Referring again to the drawings, the device comprises two frame like members A and B. Each of these frame like members A 55 and B comprises two side members 10 and 11, and each of these side members 10 and 11 comprise two members hingedly connected together as at 12. As best illustrated in Figures 7 and 8, these members are held in rigid 60 position against movement about their pivotal point 12 by means of a U-shaped metal clip 13 which embraces the members and is slidably mounted thereon. To maintain the members against movement about their pivotal point 12, the U-shaped metal member 13 is moved to the position in which it is shown in Figure 7, and when it is desired to fold the device as illustrated in Figure 4, the member 13 is moved to the position in which 70 it is shown in Figure 8 thus moving free of the pivotal portion 12 of the members and permitting of movement of the members about said pivotal point 12.

Referring again to Figure 1, it will be noted 75 that the members 10 of each of the frames are pivotally connected as at 15, and the members 11 of the frames are pivotally connected as at 16 to permit the frames to be swung toward and away from each other. The pivotal portion 15 of the members 10 comprises a hollow tube or similar member 17, and the pivotal member of the members 11 consists of a rod or the like 18 which telescopes within the tube 17 as illustrated at 19. The rod 80 85 18 is provided with a series of teeth 20 and a spring clip 21 is adapted to engage with these teeth 20 to maintain the pivoted ends of the members 10 and 11 in adjusted spaced position. By reference to Figure 5 it will 90 be noted that the spring clip has a body portion 22 which surrounds the tubular member 17 and a projecting thumb piece 23 beneath which is mounted a spring 24. Suitable handles or finger pieces such as 25 may be provided to aid in the adjusting movement of the members A and B.

The members 10 and 11 are preferably 95 formed of wood, and have an end such as 28 inserted into metallic sleeve like members 29 100

- and secured therein by rivets or the like 30 as best illustrated in Figure 5. Each of these members 10 and 11 is provided along its outer edge with a blade like member 32 and it is 5 the function of this member to form a crease such as illustrated at 33 in Figure 6 of the drawings in the trousers leg in which the members are inserted the trousers being designated 34 in said figure.
- 10 The free ends of the members 10 and 11 of each of the frame like members A and B are connected by an adjustable means which in the present embodiment of the invention comprises a tubular member 38 secured as at 15 39 to the members 10 and a bar or the like 40 secured as at 41 to the members 11. The bars 40 are provided with teeth or the like 42, and have telescoping engagement with their respective tubular member 38, and a 20 spring clip such as 21 heretofore described and designated 43 is employed as heretofore described.

Otherwise expressed, the invention forming the subject of this application might be 25 said to be in the form of a pair of frames consisting of side members having hinge plates with the hinge plate of one frame interlocked with the hinge plate of the other frame while the hinge pins 17 and 18 which 30 join the hinge plates are extended beyond the hinge plates into interfitting relation as shown in Figure 1 so that corresponding adjustment of the two frames may be effected by an adjustment of the overlapping portions 35 of the hinge pins 17 and 18.

From the foregoing described construction, it will be apparent that the frame like members A and B are pivotally connected to each other, and that the members 10 and 11 of 40 each frame like member are adjustable in directions toward and away from each other to fit varying sizes of trousers legs.

In use, the members A and B are inserted in separate legs of a pair of trousers and 45 after being properly positioned therein, the adjusting devices are operated to provide the necessary adjustment between the members 10 and 11 to place the trousers under tension and cause the blade like members 32 to form 50 a sharp crease as 33 in the trousers legs.

After the device has been left in a pair of trousers sufficient length of time, the trousers will be stretched, the bags removed from the knee thereof and the trousers legs will 55 be formed with a crease extending throughout the length thereof in the proper position relative thereto.

From the foregoing it will be apparent that the present invention provides a new and improved trousers stretcher in which the trousers may be properly shaped merely by inserting the device into the legs of the trousers and placing said trousers legs under tension by adjustment of the parts.

60 65 While the invention has been herein illus-

trated in a preferred form, it is to be understood that the invention is not limited to the specific construction herein shown, but that it may be carried out in other forms without departing from the spirit thereof.

Having thus described the invention, what is claimed as new and what it is desired to secure by Letters-Patent of the United States, is;

1. In a stretcher for trousers, a pair of frames having spaced side members, hinge plates secured to said side members, hinge pins extending through said hinge plates to hingedly join said pair of frames and extended beyond said hinge plates, the extended portions of said hinge pins being slidably associated, and a locking device on the extended portions of said hinge pins for securing the side members of each frame in corresponding adjustment. 75

2. In a stretcher for trousers, a pair of frames having spaced side members, hinge plates secured to the upper portions of said side members, hinge pins extending through said hinge plates to hingedly join said pair of frames and extended beyond said hinge plates, one of said hinge pins being of tubular formation and adjustably receiving the other hinge pin, a latch means carried by one of said hinge pins, the other hinge pin being provided with notches for engagement by said latch, and means remote from said hinge pins for adjustably connecting the side members of each frame. 90

In testimony whereof we affix our signatures. 95

HENRY SONDERSEN.
HENRY GLEMMING.
